Fig. 10.

Fig. 9.

A technical cross-sectional drawing of a cylindrical part. The drawing shows a central circular area with concentric lines, surrounded by various features labeled with numbers. Labels include: 11 at the top, 12 at the top right, 13 at the bottom right, 14 at the bottom left, 15 at the top left, 16 at the bottom left, and 17 at the bottom right. The drawing uses hatching and cross-hatching to distinguish different parts of the component.

UNITED STATES PATENT OFFICE

WALTER S. SHAW VAN, OF PHILADELPHIA, PENNSYLVANIA

GAME-SCORING DEVICE

Application filed April 24, 1929. Serial No. 357,869.

My invention relates to game scoring device and one of my main objects is to provide means for visualizing on a miniature football field or gridiron the progress of the play of a football game as it is reported by telegraph, telephone, or radio announcement. The broadcasting of the plays in a football game so that those not in attendance may be fully and immediately informed thereof has become a feature of the football season and by my device not only may the movement of the football be accurately depicted on a smaller scale and thus enable the onlookers to visualize the exact status of the game as it proceeds, but I have also provided means whereby the scoring, the number of the down, the number of the quarter period being played, the number of minutes remaining to be played and the distance which the ball must be advanced by the team in possession may be duly recorded, all of which contribute greatly to the pleasure and information of the observers.

Another object of my invention is to provide means whereby the tapes or flexible bands upon which are imprinted or otherwise displayed spaced numerals for indicating scores and yardage, are kept taut and movable either backwardly or forwardly, the tapes or bands being necessarily of considerable length and, in my device, carried by two spaced reels or spools.

Other objects and features will appear in the following description, accompanying drawings, and annexed claims.

My device is made of a convenient size so as to be portable and to be conveniently placed on a household table, and preferably the frame within which the several parts are contained is made of wood or other like material.

In the drawings, in which like numerals designate like parts in the several figures, Fig. 1 is a top plan view of one embodiment of my device; Fig. 2 is a reverse bottom plan view with the bottom member partly broken away; Fig. 3 is a longitudinal section on the line 3—3 of Fig. 2; Fig. 4 is a longitudinal section on the line 4—4 of Fig.

1; Fig. 5 is a longitudinal section on the line 5—5 of Fig. 1; Fig. 6 is a detailed plan view of the tape winding unit; Fig. 7 is a fragmentary horizontal section on the line 7—7 of Fig. 3; Fig. 8 is a transverse section on the line 8—8 of Fig. 7; Fig. 9 is a fragmentary transverse section on the line 9—9 of Fig. 1 and Fig. 10 is a detail view of a flag post and flag holder which may be used with my device.

The frame 1, which preferably is rectangular and made of wood, comprises a top section 2, a bottom section 3, end panels 4, a rear panel 5 and a front panel 6, the several frame members being secured together by screws 7. Extending longitudinally within the frame 1, between the end panels 4 and spaced from the front panel 6, is the support member 8 and extending from the rear panel 5 to the support 8 are cross pieces 9 and 10 which are provided, respectively, with openings 9' and 10' for the purpose hereinafter described.

The top section 2 is recessed at 11 to provide a seat between the panels 4, 5 and 6 for the edge of the chart 12 upon which is depicted the usual football field or gridiron 13. The chart 12 may be formed from cardboard or any other suitable material. The bottom section 3 is recessed at 14 to provide a seat between the panels 4, 5 and 6 for the edge of the base 15 which may also be formed from cardboard or other suitable material. The chart 12 is provided with a slot 16 longitudinally and centrally disposed therein within which a miniature football 17 is adapted to be moved longitudinally, being carried by the cord 18 which tracks in pulleys 19—20 and passes through the openings 9' and 10' in cross pieces 9 and 10, pulley 19 being rotated by the shaft 21 to which it is locked by the screw 22, the shaft being rotated by the turning of the hand knob 23 secured to the shaft by the set screw 24. A suitable bracket 25 provides a bearing for the inner end of shaft 21, the outer end of which is journaled in the panel 6, support for the shaft intermediate its end being provided by the member 8 and the bracket 26, a pulley 27 being mounted on

the shaft between the bracket 26 and the member 8. A coiled spring 28 on the shaft 21 engaging the shaft collar 29 retains the shaft in operative position.

5 The pulley 20 is loosely carried by the shaft 30, the inner end of which is supported in the bracket 31, its outer end being journaled in the panel 6 and provided with a hand knob 32 secured thereto by set screw 33. Intermediate its ends the shaft 30 is 10 journaled in the support member 8 adjacent to which the pulley 34 is mounted on shaft 30, being positioned by the set screw 35. A coiled spring 36 on the shaft 30 engaging the collar 37 retains the shaft in 15 operative assembly.

Secured to the cord 38 which passes 20 through the openings 9' and 10' in cross pieces 9 and 10 and tracks in the pulleys 27 and 34 is a distance marker 39 which represents a distance of ten yards, the required 25 yardage to be gained by the team in possession of the ball in four downs under the present rules of the game. The spaced standards 40 of the marker 39 project upwardly through the slot 41 provided in the chart 12, slot 41 extending substantially the 30 length of the gridiron 13, the marker 39 being movable therein by the cord 38 as the latter travels over pulleys 27 and 34, pulley 34 being the driving pulley and rotated by the shaft 30 which is turned by the hand knob 32. It will now be seen that the football 17 may be moved in accordance with 35 the plays of the game along the gridiron so that the operator of my device and on-lookers may have a correct visualization of the position of the football relative to its distance from the goal lines at all times during 40 the progress of the game and by the movement of the distance marker the necessary yardage for the gaining of a first down will be visualized for the observers.

In my device I have also provided means 45 for indicating the number of the down and the quarter period being played, these comprising spools 42 and 43 of similar construction having the numerals 1, 2, 3, and 4 displayed thereon circumferentially which, 50 as the spools are rotated, are consecutively brought into registration with openings 44 and 45, respectively, provided in the chart 12 through which they may be seen by the observers. The spools 42 and 43 are secured to axles 46 and 47, respectively, the inner ends of which are journaled in the support member 8 and the outer ends in the front panel 6, being rotatable by the hand knobs 48 and 49 respectively.

60 In order that the number of minutes remaining to be played in any quarter period may be known to the observers I have provided an endless tape 50 upon which are displayed the numerals 1 to 15 inclusive, 65 fifteen minutes being the maximum length

of a period under the present rules. Tape 50 is carried by two spools 51 and 52, the former being the driving spool and the latter the driven. Spool 52 is provided with an axle or spindle 53, the ends of which are 70 journaled in the support 8 and the front panel 6. Spool 51 is provided with an axle 54 the inner end of which is journaled in the support member 8 and the outer end in the front panel 6 and is adapted to be rotated by the hand knob 55. The proper numeral to indicate the number of minutes remaining to be played may be brought into registration with the opening 56 by moving the tape 50 over the spools 51 and 52. 75 80

The arrow 57 is pivotally mounted on the chart and may be manually turned so that it will point towards the goal line of the team having possession of the ball.

The tapes bearing the numbers for indicating the scores of the contesting teams and also for indicating the numbers of yards to be gained are necessarily of extended length to contain the multiplicity of required numbers, the numbers being desirably of such 90 size that they may be easily read, and I have provided an improved means whereby the tapes may be kept taut and kinking or distortion thereof prevented as they are moved forwardly and backwardly so as to register 95 the proper number, as the play progresses, with the proper opening in the face of the chart to make it visible to the operator.

My improved means, a detailed plan view of which is shown in Fig. 6 and three 100 embodiments, A, B and C, of which are preferably used in my game scoring device to indicate the respective scores of the contesting teams and the number of yards to be gained, comprises two spools 58 and 59, 105 to each of which one end of the tape 60 is secured by an adhesive or any other suitable means, more or less of the tape being wound on each spool as the indicated number of the numeral is changed. The inner 110 ends of the axles 61 and 62, respectively, of the spools 58 and 59 are journaled in the support 8 and their outer ends in the front panel 6, the outer end of axle 61 of the driving spool 58 projecting slightly without the 115 panel 6 to enable a hand knob 63 to be secured thereto by set screw 64.

The spools may be conveniently formed from wood by a lathe and comprise annular flanges 65 and 66 suitably spaced to form a guideway for the retention therebetween of the tape 60. The outer ends of the spools are flanged and grooved to form sheaves 67 and 68 over which the belt 69 runs. The belt 69 is preferably a steel coil spring, its ends being disengageable, and the tension maintained by the belt is desirably such as to permit a minimum of lag in the driven sheave 68 as it is rotated. The driving sheave 67 is preferably of greater diameter 125 130

than that of the driven sheave 68 whereby the latter rotates more rapidly than the former.

Secured to the inner face of the sheave 68, in any suitable manner, as by pins, is a ratchet wheel 70 and within the outer end of the spool 59 is provided a recess 71 for the retention therein of a spring metal band 72, one end of which is held within the saw cut 73, the other end being bent to form a spring pawl 74 with which a tooth of the ratchet wheel 70 engages as the latter is rotated in a counter-clockwise direction by the belt 69, thereby causing the spool 59 to rotate in like direction and wind upon it the tape 60 as the latter unwinds from the spool 58. As will be seen, the rotation by the operator of the knob 63 will cause the belt 69 to travel in the same direction as that of the knob rotation, the spools 58 and 59 being likewise rotated by the engagement of the belt 69 with the sheaves 67 and 68 fitted to the axles 61 and 62 respectively. It will be further evident that when the spools 25 are rotated in clockwise direction the pawl 74 is disengaged from the teeth of the ratchet and rotation of spool 59 is not affected thereby except that the friction between the ratchet and the pawl may retard somewhat the speed of rotation of the spool 59 and assist in maintaining desired tension on the tape 60.

To prevent too free rotation of the spool 59 and to assist in providing desired tension upon the tape 60 to keep it taut and free from kinking or distortion, a coil spring 75 is preferably mounted upon the outer end of spool 59, one end 76 of the spring being secured in a suitable aperture 40 in the bracket 77 and the other end bearing slidably against the adjacent annular flange on the spool. The spring 75 surrounding the spool 59 will exert a frictional drag and braking action against and prevent too rapid rotation of the spool thereby assisting in keeping desired tension upon the tape as it is moved in either direction.

When a larger number on the tape than that which is then visible is desired to be brought into registration with the adjacent observation opening, the driving spool 58 is rotated in clockwise direction which draws the tape from the driven spool 59 and when a smaller number is to be registered the driving spool is rotated counterclockwise whereby the pawl and ratchet are brought into engagement by the action of the belt upon the sheaves and the driven spool is rotated counter-clockwise drawing the tape from the driving spool and winding it upon the driven spool. Inasmuch as the diameter of the driven sheave 68 is smaller than the diameter of the driving sheave 67, sheave 68 will rotate more rapidly than sheave 67, resulting in spool 59 drawing the tape to itself

faster than the tape is released from spool 58 and thereby maintaining desired tension upon the tape, which tension, however, is prevented from becoming too great by the tendency of the belt 69 to slip slightly on the sheaves when the tension of the tape causes too great resistance to rotation of the driven spool. Thus a suitable tension on the tape is maintained at all times and a smooth and even passage of the numerals in registration with the observation openings is effected. Exact control of the exposed number is accomplished by rotation of the hand knob, the tape by reason of its being maintained desirably taut being sensitively responsive to the rotation of the knob in either direction. Another advantage of my tape winding device is that but one hand knob is employed to move the tape in either direction.

A spacer disk 78 loosely fitting the axle 62 is provided whereby upon the withdrawal of the axle therefrom and from the spool 59, the latter may be conveniently disengaged from the ratchet.

In my device I have also provided goals 79 and 80 comprising standards and a cross bar, the standards being removably erected in suitable openings in the chart 12.

To assist in the better visualization of the play of the game I have provided flag poles 81 and 82 which may be removably positioned in suitable openings in the chart 12, the poles having adjacent their top a spring clamp 83 into which may be removably inserted miniature pennants or flags of the contesting teams, the pennants or flags being readily interchangeable as the goals are changed during each quarter period.

While I have herein described with considerable particularity a preferred embodiment of my invention, I do not thereby desire or intend to specifically limit myself to the precise details of construction and arrangement of parts to which I have referred as the same may be modified and varied from the forms shown in the drawings and herein described without departing from the spirit and scope of the invention as defined in the appended claims nor do I hereby intend to restrict the use of my improved tape winding mechanism to the particular game scoring device herein described.

Having thus described my invention, I claim and desire to protect by Letters Patent of the United States:

1. A device for visualizing the progress of the play of a football game, comprising a frame, a chart mounted within the said frame, a simulation of a football field upon said chart, a slot extending longitudinally of said field, a miniature football movable within the slot, a second slot extending longitudinally of said field, a distance marker

movable within the second slot, and cooperating operating means for moving the football and the distance marker along the said slots having separate operating devices 5 independently operable to move either the ball or the distance marker.

2. A device for visualizing the progress of the play of a football game, including a frame, a chart mounted within said frame, a simulation of a football field upon said chart, a slot extending longitudinally of said chart, a miniature football movable within said field, a second slot extending longitudinally of said field, a distance marker movable within the second slot, and cooperating operating means for moving the football and the distance marker along the slots comprising spaced shafts, pulleys mounted on the shafts, each shaft having one of the pulleys fixed to it, and cords arranged on the pulleys and connected with the football and the distance marker, and separate means for operating the shafts and moving the football and the distance marker independently of each other.

3. A device for visualizing the progress of the play of a football game including a frame having a simulation of a football field, a slot extending longitudinally of the field, a miniature football movable within said slot, a second slot extending longitudinally of the said field, a distance marker movable within said second slot, cooperating means for moving the football and the distance marker having separate operating devices located at one side of the field and independently operable to move either the football or the distance marker, spools rotatably supported within the frame at one side of the field, and numeral bearing tapes carried by the spools and indicating the scores, the yardage to be gained, the number of periods to be played, the number of downs, and the number of minutes remaining to be played, said spools being manually rotatable and the tapes cooperating with the football and distance marker for enabling the successive plays of the game to be reproduced visually.

50 4. A device for visualizing the progress of the plays of a football game, including a frame having a simulation of a football field, spaced driving and driven spools located at one side of the field, a tape adapted for indicating the scores, the yardage to be gained, the number of downs, the number of minutes remaining to be played, or the like, said tape having one end attached to the driving spool and the other end attached to the driven spool, sheaves connected to each spool, a belt tracking in said sheaves, a hand knob for rotating the driving spool, and means for governing the speed of rotation of the driven spool, whereby the tape between the spools is maintained taut.

5. A device for visualizing the progress of the plays of a football game, including a frame having a simulation of a football field, spaced driving and driven spools located at one side of the field, a tape adapted for indicating the scores, the yardage to be gained, the number of downs, the number of minutes remaining to be played, or the like, said tape having one end attached to the driving spool and the other end attached to the driven spool, a sheave integral with the driving spool, a sheave connected with the driven spool, a pawl carried by the driven spool, a ratchet wheel carried by said last mentioned sheave adapted to engage the pawl to rotate the driven spool, a belt tracking in said sheaves, and a hand knob for rotating the driving spool and its sheave.

6. A device for visualizing the progress of the play of a football game, including a frame having a simulation of a football field, spaced driving and driven spools located at one side of the field, a tape adapted for indicating the scores, the yardage to be gained, the number of downs, the number of minutes remaining to be played, or the like, said tape having one end attached to the driving spool and the other end attached to the driven spool, a sheave integral with the driving spool, a sheave connected with the driven spool, a pawl carried by the driven spool, a ratchet wheel carried by said last mentioned sheave adapted to engage the pawl to rotate the driven spool, a belt tracking in said sheaves, a hand knob for rotating the driving spool and its sheave, and means for governing the rotation of the driven spool, whereby the tape extending between the spools is maintained under tension.

7. A device for visualizing the progress of the play of a football game, including a frame having a simulation of a football field, spaced driving and driven spools located at one side of the field, a tape adapted for indicating the scores, the yardage to be gained, the number of downs, the number of minutes remaining to be played, or the like, said tape having one end attached to the driving spool and the other end attached to the driven spool, a sheave integral with the driving spool, a sheave connected with the driven spool, a pawl carried by the driven spool, a ratchet wheel carried by said last mentioned sheave adapted to engage the pawl to rotate the driven spool, a belt tracking in said sheaves, a hand knob for rotating the driving spool and its sheave, and a coil spring on the driven spool for assisting in retarding the speed of rotation thereof, whereby the tape between the spools is maintained under tension.

8. A device for visualizing the progress of the play of a football game including a frame having a simulation of a football

field, driving and driven spools located at one side of the field, a tape having one end attached to the driving spool and the other end attached to the driven spool and having numerals for indicating scores, yardage to be gained, the number of downs, or the like, sheaves connected to each spool, a belt tracking in said sheaves, a hand knob for rotating the driving spool, and means for governing the speed of rotation of the driven spools, whereby the tape between the spools is maintained taut.

In witness whereof, I have hereunto set my hand this 23rd day of April, 1929.
